UNITED STATES PATENT OFFICE.

MATTHIAS T. LA ROUCHE AND FRANK S. BAKER, OF UTICA, NEW YORK.

DESIGN FOR A MATCH-SAFE.

SPECIFICATION forming part of Design No. 27,776, dated October 26, 1897.

Application filed March 22, 1897. Serial No. 628,783. Term of patent 31 years.

To all whom it may concern:

Be it known that we, MATTHIAS T. LA ROUCHE and FRANK S. BAKER, citizens of the United States, residing at Utica, in the county of Oneida and State of New York, have invented and produced a new and original Design for a Match-Safe, of which the following is a specification, reference being had to the accompanying drawings, showing the same.

5 The figure shows a perspective view of our design of match-safe.

The feature of our design is the shape and appearance of the match-safe as embodied in the base 1, standard 2, and oblong receptacle

3, as shown, and arranged as shown in the 15 drawings.

What we claim is—

The design of a match-safe substantially as herein shown and described.

In witness whereof we have hereunto affixed our hands, at Utica, New York, this 13th day of March, 1897, in the presence of two witnesses.

MATTHIAS T. LA ROUCHE.
FRANK S. BAKER.
